Act,

UNITED STATES PATENT OFFICE.

BERT BARRY, OF MOUNT EDEN, AUCKLAND, NEW ZEALAND.

ELECTRICAL WATER HEATER.

Application filed June 19, 1926, Serial No. 117,107, and in New Zealand August 31, 1925.

This invention relates to electrical water heaters in which heating element containers are inserted into a water circulating container.

5 The object of the present invention is to enable the heating elements to be easily removed and inserted, to improve generally the construction of such heaters, and also to ensure that the diffusion of heat from the total 10 available element surface will be utilized.

According to my present invention, a water chamber of desired section is provided with two or more element containers passing through the chamber. These containers in 15 section are shaped according to the sectional shape of the heating elements to be inserted therein, and are open at both ends of the chamber and securely fixed in the ends of the chamber, the walls thereof being not 20 thicker than necessary in order to enable as much heat as possible to pass from the heating elements through such walls.

The heating elements are preferably flat in section, constructed so as to fit neatly the 25 walls of the containers and suitably insulated therefrom. One end of each element is connected to another at one end of the chamber, while their other ends are connected to suitable terminals at the other end of the 30 chamber. The element containers are in pairs and a chamber may contain one or more pairs of such containers.

New elements may be inserted by withdrawing the elements from one end of the 35 chamber and sliding the new ones in position.

Inlet and outlet pipes lead to and from the chamber to provide the required circulation.

40 The invention will be illustrated with the aid of the accompanying drawings, wherein:—

Figure 1, is an elevation of the water chamber.

45 Figure 2, is a plan of the chamber.

Figure 3, is a longitudinal sectional elevation on line C—C Figure 2.

Figure 4, is a sectional plan on line B—B, 50 Figure 3.

Figure 5, is a sectional elevation on line A—A Figure 1.

Figure 6, is an elevation of the heating element.

55 Figure 7, is a plan of the heating element.

Figure 8, is a section of a heating element. Referring to the drawings, a water chamber

1 is formed of a circular wall 2 and end walls 3 and 4. Passing longitudinally through the chamber are element containers 5, flat in section, as shown in Figure 4, 60

and open at both ends of the chamber. These containers are secured in the end walls 3 and 4 by brazing, these walls being as thin as would be consistent with strength. An inlet pipe 6 leads to and an outlet pipe 7 leads 65

from the chamber 1 to provide the required circulation. A chamber 8 at one end of the chamber 1 is formed by a wall 9 and closed by a plate 10 secured to the wall 9 by screws 70

11. A sheet of mica 12 and a sheet of asbestos 13 (see Figure 5) provide insulation at the upper end of this chamber. The wall 3 has a circular projecting wall 14 to receive the insulating plate 15 (see Figure 5), of a connecting device of ordinary type. The 75

containers 5 receive heating elements 16 composed of strips of mica 17, upon which is wound a suitable wire 18 (see Figures 6 and 8), preferably flat nichrome wire. Strips of mica 22 (Figures 6 and 8) are then placed 80

on either side and the whole clamped together by metal bands 19. The wires of each element at one end are connected by metal plates 20 secured together by a screw 21 so as to make good contact. The other end 85

of the wires 18 are connected to a plate 23 (Figure 6) from which lead flexible connecting wires 24 for attachment to the terminal screws 25 in the plate 15 (see Figure 5). As will be seen from Figure 8 the outer surfaces 90

of the mica strips 22 of the heating elements bear closely against the inner surface of the walls of the element containers 5 so that heat from the wires will be conveyed as directly as possible through such walls. The plates 95

20 are insulated from the end wall 4 by mica strips and asbestos strips 26 (see Figure 5).

The elements are inserted or removed by removing the insulated end plates 10 gripping the plate 20 and simply sliding the 100

elements out of position. Thus the removal, and replacement of the elements become a very simple matter.

The pipes 6 and 7 may lead to any desired form of reservoir or the like.

105 What I claim is:—

1. In a water heater, the combination with a water chamber provided with an inlet and outlet pipe respectively, of heat conducting containers of thin metal and flat section arranged in pairs and fixed in the end walls of said chamber and open at both ends, electric 110

heating elements extending through said containers in close contact with the walls thereof and having a sliding fit thereby transmitting heat direct to the walls of said containers, and means detachably connecting the ends of each pair of said heating elements of each pair of containers so as to retain the said heating elements in position, while enabling one pair to be withdrawn or 10 inserted at will.

2. The water heater as specified in claim

8, including an insulating strip on each side of said heating elements producing a sliding fit with the interior of said containers, metal plates fixed to said elements at one end thereof and bent at their ends, means connecting said bent ends, and a plate at the other end of said elements for attachment of lead wires to terminals.

In testimony whereof I affix my signature.

BERT BARRY.
